REFRIGERATING APPARATUS

Philmore F. Sperry, Chicago, Ill., assignor to Excel Auto Radiator Company, Chicago, Ill., a corporation of Delaware

Application April 25, 1938, Serial No. 203,990

3 Claims. (Cl. 62—146)

My invention relates to refrigerating apparatus and is designed particularly for use on an automobile equipped with a cooling device comprising a radiator through which a cooling fluid is designed to be circulated and having means for causing a stream of air to flow through the radiator so as to be cooled thereby. It is the object of my invention to provide an improved unit form of apparatus for cooling a supply of water and forcing it through a cooling radiator, such unit being arranged so as to be suitable for effective use at any point on a motor vehicle where room can be found for mounting it.

In working out my improved arrangement, it has been one of my objects to provide a mechanism which shall be effective in operation, which may be produced at low cost by the use of parts capable of being easily produced and assembled, which shall be so simple in construction and arrangement as to enable anyone with very little mechanical skill or knowledge to operate it successfully, which may be easily and quickly mounted in operative condition upon a motor car, and which shall be effectively operative by the use of materials readily available to motorists without the necessity for a search therefor. To this end, I have employed for my apparatus an improved insulated tank arranged to have a suitable supply of ice supplied thereto; a pump for taking water from the tank and forcing it to the desired point of use and then returning it to the tank for renewed cooling; and a motor for operating the pump, the pump and motor being of such size and arrangement as to be instrumental for producing an effective flow of water through the tank while at the same time being capable of being operated with a low expenditure of electric current so as not to drain the car battery, the parts being so arranged and so related as to operate with high efficiency for the attainment of my objects.

It is another object of my invention to improve devices of this type in sundry details hereinafter pointed out. The preferred means by which I have accomplished my several objects are illustrated in the accompanying drawings, in which

Fig. 1 is a vertical sectional view through the preferred form of my improved apparatus, being taken substantially at line 1—1 of Fig. 2.

Fig. 2 is a horizontal sectional view taken at the line 2—2 of Fig. 1.

Fig. 3 is a vertical sectional view taken at the line 3—3 of Fig. 1.

Fig. 4 is a vertical sectional view taken on a considerably enlarged scale at line 4—4 of Fig. 1.

Fig. 5 is a view showing the construction of the water pump, substantially as seen at the line 5—5 of Fig. 4, and

Fig. 6 is an enlarged detail view of the upper left hand corner portion of the device as shown in Fig. 1.

Referring now to the several figures of the drawings, in which corresponding parts are indicated by the same reference characters, 10 indicates a tank member preferably formed of sheet metal wall sections separated by insulation material 11 of any suitable type. The tank member 10 is closed at the top by means of a lid member 12 likewise formed of sheet metal wall sections separated by insulation material 11, the lid being 15 movably mounted in position by means of hinges 13 of any suitable type. In the arrangement shown a handle 14 is provided on the top face of the lid or cover member 12, and an ordinary trunk latch structure 15 is provided for holding 20 the lid releasably in closed position. In the arrangement shown, a gasket 16 preferably formed of rubber is provided between the lid and the upper edge of the body 10 of the tank, such gasket being held in position by reason of its 25 undercut relation with respect to the body of the tank. The arrangement is such that a supply of ice within the tank is thoroughly insulated from the surrounding atmosphere so as to be preserved effectively within the tank.

On the outer face of the tank, I have provided a heavy metal plate 17 in the form of a channel, such plate being secured in position across the bottom edge portion of one end of the tank by means of bolts 18, as is best shown in Fig. 2. 35 The heads of the bolts 18 are preferably covered with solder so as to prevent the leakage of water around the bolts. In the arrangement shown, a gasket 19 is interposed between the plate 17 and the end of the tank.

On the outer face of the plate 17, I have mounted an electric motor 20 which is held in position by means of a bracket 21 bent into the shape of a cradle for fitting the side of the motor. In axial alignment with the motor 20 I have provided a pump 22 supported in position by means of a bracket 23. As is best shown in Fig. 4, the motor shaft 24 is connected with the shaft 25 of the pump by means of a wire coil 26 which surrounds the ends of the shafts and is secured thereto by means of solder or in any other suitable manner, the coil being wound in the direction so as to cause it to contract upon the application of power from the motor to the pump. The coil 26 constitutes in effect a universal joint con-

30

nexion between the shafts so as to obviate the necessity for careful and accurate alignment of the shafts with respect to each other.

As is best shown in Figs. 4 and 5, my pump 22 comprises a hub portion 21 provided with a plurality of outwardly extending vanes or paddles 28 adapted to be rotated by the shaft 25 within the pump chamber 29. The pump casing is provided at one side with an outlet nozzle 30 leading 10 tangentially from the chamber and having an outlet pipe 31 connected therewith. An inlet pipe 32 is connected with the pump chamber 29 by means of a nozzle member 33 opening into a housing member 34 which is formed with the 15 closure plate 35 of the casing of the pump, the housing 34 providing an axial extension of the pump chamber through which water entering through the inlet pipe 32 is afforded access to the vanes 28. The arrangement is such that 20 upon rotation of the pump in counterclockwise direction in Fig. 5 fluid is forced out through the pipe 31 so as to establish a suction effect within the chamber 29 for causing water or other fluid to be drawn in through the pipe 32.

25 For protecting the motor 20 and the pump 22 and their connections, I have provided a shield 36 which in the arrangement shown is formed of sheet metal secured to the flanges of the channel plate 17. As is clearly shown in Figs. 2 and 3, both ends of the shield 36 are open so as to permit an ample supply of air to be provided for cooling the motor 20.

As is best shown in Figs. 1 and 2, the pipe 32 extends through the wall of the tank member 10 so as to open within the tank near the bottom. About the open inner end of the pipe 32, I have provided a strainer comprising a plate 37 bent into the shape of a housing, being provided with a great number of openings 38 through the 40 plate and having a fine wire mesh 39 stretched about the housing so as to act as a strainer for the water passing out through the pipe 32. By the use of such a strainer having a comparatively very large screen surface, the ice in the tank is 45 kept from clogging up the end of the pipe 32.

In one side wall of the tank member 10, I have provided an inlet pipe 40 extending lengthwise along the wall of the tank and opening into the tank in spaced relation from the bottom. The 50 pipes 40 and 31 extend upwardly through the top wall of the shield, in the arrangement shown passing through the top flange of the channel bar 17 rather than through the shield member 36. Such pipes are designed to be connected by 55 any suitable means with the radiator of a cooling device mounted on the dashboard or at any other suitable part of the car upon which the tank is mounted. The arrangement is to be such that the water taken from the tank 10 by the 60 pump 22 is forced through the pipe 31 and its connections to the cooling radiator as above suggested and is returned from such radiator to the tank 10 through the pipe 40 and its connections. In the arrangement shown, the inner end portions of the pipes 32 and 40 are soldered to the 65 inside metal lining of the tank for preventing leakage at these points.

In the arrangement shown, the tank 10 is mounted in position by means of clips 41 which 70 engage the plates 42 secured at opposite ends of the tank on its bottom face, as is clearly shown in Fig. 3.

By the use of my improved construction, I have provided a unit form of cooling device which is 75 supplied ready for mounting upon a pleasure car

or a truck at any point where room is found for the tank. The shield 36 provides ample protection for the working parts so as to protect them from damage. The motor and pump are of such size and arrangement as to be effective for taking 15 a substantial amount of water from the tank 10 and returning it to the tank for renewed cooling after such water passes through a cooling radiator. The motor 20 is preferably to be driven by current from the usual storage battery of the 10 car or truck. The connections between the unit and the cooling radiator will ordinarily be effected by the use of rubber hose which are adapted to be slipped easily into position upon the ends of the pipes 31 and 40.

15 While I prefer to employ the form and arrangement of parts as shown in my drawings and as above described, it is to be understood that my invention is not limited to the apparatus as shown except so far as the claims may be so limited, it being understood that changes might well be made in the form and arrangement of parts without departing from my invention.

I claim:

1. A refrigerating apparatus particularly arranged for movement as a unit, said apparatus comprising an inner tank adapted to hold a supply of ice and water, an outer tank surrounding said inner tank and in spaced relation thereto, heat insulating medium packed between said tanks, an outlet pipe passing through corresponding corners of said tanks, a return pipe having an opening through the inner tank in proximity to the diagonally opposed corner of the tank from said outlet pipe, said return pipe 30 passing through the insulated space between the tanks and emerging from the outer tank at the same side thereof as said outlet pipe, a motor and pump unit mounted on the outside of said tank between said pipes, and a shield for the motor and pump unit, said shield being in the form of a housing member providing a tunnel open at its ends at opposite sides of the motor for affording free passage of cooling air through the motor.

2. A refrigerating apparatus particularly arranged for movement as a unit, said apparatus comprising a substantially rectangular tank adapted to hold a supply of ice and water, inlet and outlet pipes having openings into the tank located at substantially diagonally opposed corners thereof and emerging from the tank at the same side of said tank, a mounting plate secured to the tank at said side, a motor and pump unit supported on said mounting plate with the pump operatively connected with said outlet pipe, and a tunnel-shaped shield covering the motor and pump unit and open at both ends at opposite sides of the motor so as to afford a free flow of cooling air for said unit, said pipes and motor and pump unit being mounted on the same side 60 of the tank so as to be readily accessible.

3. A refrigerating apparatus particularly arranged for movement as a unit, said apparatus comprising a substantially rectangular tank adapted to hold a supply of ice and water, inlet and outlet pipes communicating with said tank at substantially diagonally opposed corners thereof and passing to one side of said tank motor and pump means secured to said side of said tank with the pump connected with said outlet 70 pipe, and a lid for the tank, said lid being hinged to the tank at said side whereby the motor and pumping means are shielded by the lid when the supply of ice in the tank is renewed.

PHILMORE F. SPERRY. 75
